(57) **CLAIM**

The ornamental design for a toothbrush body, as shown and described.

DESCRIPTION

FIG. 1 is a perspective view of a toothbrush body embodying our new design, the head portion of said toothbrush body being illustrated as having a plurality of holes therein for the insertion thereinto of bristles tufts;

FIG. 2 is a top plan view thereof;

FIG. 3 is a left side elevational view thereof;

FIG. 4 is a bottom plan view thereof;

FIG. 5 is a front end view thereof taken from the free end of the head portion of said toothbrush body; and,

FIG. 6 is a rear end view thereof taken from the free end of the handle portion of said toothbrush body.
